PROCESS FOR TREATING HYDROCARBON OILS

Gustav Egloff, Chicago, Ill., assignor to Universal Oil Products Company, Chicago, Ill., a corporation of South Dakota

Application October 31, 1930, Serial No. 492,399

2 Claims. (Cl. 196—144)

This invention relates to the treatment of hydrocarbon oils.

It further relates to processes for improving the character of hydrocarbons by subjecting them to photochemical influence.

It is a feature of the invention to treat hydrocarbon oils in the presence of chemical agents which will improve the character of the oils, as by decreasing the gum and sulfur content and by increasing color stability.

More particularly, the invention pertains to a process for effecting the simultaneous elimination of gum-forming components, gums and sulfur containing compounds from light hydrocarbon oils, and in its more specific aspect it comprises the chemical treatment of oils in the presence of light, preferably ultra-violet light, to effect this result.

It is known to the art that gums and gum-forming components of light mineral oils, such as cracked distillates, may be acted upon in the presence of certain agents such as zinc and copper chlorides, or other salts, to facilitate their removal. Such treatment may produce a color-stable oil. Ordinary treatment of oils with zinc chloride or its equivalent, effects no substantial desulfurization, and subsequent treatment is necessary for diminishing the sulfur content.

In accordance with the practice of this invention, however, it has been found that light rays, and particularly ultra-violet light, have a beneficial effect on the activity of metal salts, such as zinc chloride, when utilized in the treatment of hydrocarbons, a substantial desulfurization taking place simultaneously with the removal of the gum and gum-forming constituents.

In the carrying out of the preferred form of the process embodying the invention, ultra-violet light will be used, but the character of light rays may be varied from the short wave portion of the spectrum through the visible portion and into the infra-red portion. The sun's rays or artificial light closely approximating the character of the sun's rays may be employed.

It will be understood that the invention is not to be limited as to the character of the reagents used, or the specific steps outlined in the preferred form of the process to be hereinafter described. The following description of the apparatus as illustrated in the drawing, and of the process employing the apparatus, is to be taken merely as illustrative of the features of the invention.

Referring to the drawing, the oil to be treated is supplied through line 1 and valve 2 to pump

3 and is fed therefrom through line 4, valve 5, line 6 and valve 7 into heating element 8, which is located in any suitable form of furnace 9 and in which the oil is heated under any desired pressure conditions, preferably to a temperature sufficient to effect subsequent vaporization of substantially all of the distillate.

A treating agent, such as, for example, a solution of zinc chloride and water, supplied through line 10 and valve 11 to pump 12, may be fed through valve 13 in line 6, combining therein with the oil to be treated, and passing through valve 7 to heating element 8.

If the material supplied to heating element 8 is a distillate, such as that ordinarily produced by the cracking of heavier oils, which comprises a substantial proportion of material boiling within the range of motor fuel and heavier components boiling above the range of motor fuel, the treating process here described preferably also embodies redistillation of the distillate to effect separation of the motor fuel components from the heavier components of the distillate. If, however, the oil to be treated corresponds substantially in boiling range to motor fuel, the heating to which it is subjected in heating element 8, may be simply for the purpose of vaporizing the oil or may be employed for the purpose of increasing the activity of the treating agent introduced to the heating element together with the oil as already described.

Heated materials from heating element 8 are discharged through line 14 and valve 15 into the lower portion of treating and fractionating column 16. Column 16 may be of any suitable form of contacting or fractionating device, such as a packed or bubble tower or a column containing perforated pans, or the like, through which the heated vapors rise and are intimately contacted with a treating agent, such as a solution of zinc chloride and water, which is supplied through line 17 and valve 18, and fed by means of pump 19 through line 20 and valve 21 to the treating and fractionating column 16.

Treating and fractionating column 16, aside from its function as a treating column, in which the chemical reagent is contacted with the oil, may serve as a fractionating zone to effect separation of the lighter from the heavier components of the oil undergoing treatment. In this case, the heavier components of the distillate are condensed and returned to the lower portion of column 16 and are withdrawn through line 22 and valve 23.

A substantial proportion, if not all, of the

water content in the solution of the zinc chloride will be evaporated by contact with the hot vapors in column 16, and the spent zinc chloride, together with sludge from the treating reaction, 5 may be withdrawn from the bottom of the column through line 24 and valve 25. A dispersion of zinc chloride in the heavier components of the oil, which are refluxed to the bottom of column 16, which dispersion may still have value 10 as a treating solution, may be withdrawn from the column through line 26 and valve 27 and recirculated by means of pump 28 through line 29 and valve 30 back into column 16, preferably at or near the mid-portion of the column. 15 A source of light, such as for example a mercury vapor bulb 31, is placed within the treating and fractionating column 16, and is supplied with electrical energy through lines 32. It will be understood that any suitable source of 20 light other than a mercury bulb, such as, for example, a carbon arc or any incandescent bulb, may be employed, and it will also be apparent that instead of locating the source of light within column 16, it may be located exterior to the column, and the light may be admitted to the interior of the column through suitable windows not shown in the drawing, in which case glass of suitable composition, well known to the art, capable of admitting the desired light rays, is 25 employed. The source of light is in all cases so located that the light rays are directed upon the oil undergoing treatment with treating solution, and to insure effective distribution of the light rays a plurality of sources of light may be employed, if desired, in which case it will be understood that each source of light may emit substantially the same or different light rays, so that the oil undergoing treatment in various portions of the apparatus may be subjected to the 30 same or to different light rays as desired.

The treated vapors from column 16 are withdrawn through line 33 and valve 34, and may be subjected to any further chemical treatment which may be desired, or may be subjected to 45 condensation, cooling and collection, by well known means not illustrated in the drawing.

The treating process embodied by the present invention may be accomplished under any desired temperature and pressure conditions. The 50 temperatures employed may range from substantially atmospheric temperatures to cracking temperatures of a high order, generally termed vapor phase cracking temperatures; and pressure employed may vary from sub-atmospheric 55 to high super-atmospheric pressures as high as 2000 pounds or more per square inch. Preferably, however, in an apparatus, such as illustrated in the drawing, the temperatures employed are below the ordinary cracking range, being only sufficient to effect redistillation of 60 the distillate. All the pressures employed are preferably substantially atmospheric or relatively low super-atmospheric pressures and may be substantially equalized throughout the system 65 or may be lower upon column 16 than upon heating element 8.

As a specific example of the operation of the process of the invention in an apparatus, such

as illustrated, a cracked distillate of about 50 degrees A. P. I. gravity, containing some 70 per cent of motor fuel, is subjected in the heating element to a temperature of approximately 600 degrees F. An 80 percent solution of zinc chloride and water amounting to about 5 percent by weight of the oil undergoing treatment is also supplied to the heating element. A pressure of about 100 pounds per square inch is maintained in the heating element, this pressure being sufficient to maintain a substantial proportion of the oil in the liquid state in this zone, but permitting the formation of steam at a temperature employed from the water in the treating solution, thus effecting dispersion of the zinc chloride in the oil being heated.

The pressure in the treating and fractionating column is reduced to substantially atmospheric pressure, permitting vaporization in substantially all of the heated oil. A 40 percent solution of zinc chloride and water amounting to approximately 10 percent by weight of the oil treated is introduced into the treating and fractionating column, passing down through the column countercurrent to the ascending vapors and being intimately contacted with these vapors in the presence of ultra-violet light supplied substantially as described.

Treated gasoline vapors are removed from the top of the treating column and are condensed 105 and collected, while pressure distillate bottoms are withdrawn from the lower portion of the fractionating column.

Aside from effecting separation of the gasoline light components of the distillate from its 110 heavier components, and reducing the gum content to some 25 milligrams as compared with about 350 milligrams of gum in the untreated distillate, the sulfur content of the gasoline may be reduced to 0.2 percent or less, as compared 115 with approximately 0.5 percent in the untreated distillate, and the gasoline may be rendered a stable water white color even after prolonged exposure to sunlight.

Having thus described my invention, what I 120 claim is:

1. A process for improving the character of hydrocarbon oils comprising vaporizing a hydrocarbon oil, refluxing the vapors, treating the vapors by commingling a non-volatile treating 125 agent capable of decreasing the gum content and of effecting a color stabilization of the oil, recirculating treating agent in the reflux condensate and commingling with said vapors, the treatment being carried on in the presence of 130 light.

2. A process for improving the character of hydrocarbon oils comprising vaporizing a hydrocarbon oil, refluxing the vapors, treating the vapors by commingling a non-volatile treating 135 agent capable of decreasing the gum content and of effecting a color stabilization of the oil, recirculating treating agent in the reflux condensate and commingling with said vapors, the treatment being carried on in the presence of ultra-violet 140 light.

GUSTAV EGLOFF.
